UNITED STATES PATENT OFFICE.

BERT H. BLOSE, OF JOHNSONBURG, PENNSYLVANIA.

LUBRICATING MEANS FOR JOURNAL BOXES.

Application filed August 5, 1922. Serial No. 579,903.

To all whom it may concern:

Be it known that I, BERT H. BLOSE, a citizen of the United States, residing at Johnsonburg, in the county of Elk and 5 State of Pennsylvania, have invented certain new and useful Improvements in Lubricating Means for Journal Boxes, of which the following is a specification, reference being had to the accompanying drawings. 10 This invention relates to journal boxes, and more particularly to lubricating means for journal boxes.

It is an object of the invention to provide means of this character wherein the 15 usual oil swab or packing is eliminated, and the journal of the axle immersed in a quantity of lubricant.

It is another object of the invention to provide means of this character substantially in the form of a receptacle capable 20 of being applied and removed from the journal box, the receptacle being of a character to hold a small quantity of oil and yet permit the major portion of the journal 25 of an axle to be immersed in the oil.

It is also an object of the invention to provide means of this character in the form 30 of a receptacle constructed to receive the journal of the axle, means being provided for spacing the receptacle from the journal box, the receptacle substantially embracing the greater portion of the journal of the axle.

It is a further object of the invention to 35 provide lubricating means of this character in the form of a receptacle adapted to receive the major portion of the journal of an axle, to permit said portion to be immersed in oil, the receptacle being provided 40 with a hinged lid to facilitate filling of the receptacle with oil and to protect the oil and prevent splashing thereof.

It is a still further object of the invention to provide means of this character including a receptacle having one end open 45 for the reception of the journal of an axle and provided with means to prevent the escape of lubricant through said end.

With these and other objects in view, the 50 invention consists in the improved construction and arrangement of parts to be herein-after more particularly described, fully claimed and illustrated in the accompanying drawings, in which:—

55 Figure 1 is a longitudinal sectional view

of a journal box showing the invention applied;

Figure 2 is a top plan and sectional view of the journal box with the invention applied; 60

Figure 3 is a section taken on the line 3—3 of Figure 1; and

Figure 4 is a longitudinal sectional view of the lubricant receptacle.

Referring to the drawings, 5 designates a 65 conventional form of journal box including a bottom 6, a front wall 7 and a rear wall 8, said rear wall being provided with the usual journal opening 9 through which the journal A of the axle B passes. The journal 70 box is provided with the usual hinged cover 10. The structure above described is well known, and forms no part of the invention.

The means previously proposed for lubricating the journals of car axles is 75 unsatisfactory, in view of the frequency of hot boxes, caused by friction of the journal and drying of the lubricant packing. This disadvantage is overcome by the novel provision of an oil cellar in the form of 80

a receptacle 11, said receptacle including side walls 12, a bottom 13, and a front wall 14. The front wall is curved in accordance with the curvature of the journal box and is also extended inwardly so as to direct 85 the lubricant toward the journal of the axle. The side walls 12 have their rear end portions enlarged or thickened as at 15 and tapered toward the center of the receptacle,

so as to decrease the distance between said 90 walls at the rear end of said receptacle. The extremity of the enlarged portion of each side wall is reduced to provide a recess 16, said recess extending through the rear end of the receptacle, the purpose of which 95 will be hereinafter described. The bottom 13 of the receptacle has its rear end portion enlarged or thickened as at 17 and tapered toward the center of the receptacle, similar to the enlarged or thickened portions of the 100 sides. It is of course obvious that the enlarged portions of the sides and bottom merge to substantially provide a rounded

bottom, the bottom, similar to the side walls, having the extremity of its enlarged portion 105 reduced to provide a recess 18, said recess merging with the recesses 16 of the walls to provide a substantially semi-circular recess at the rear end of the receptacle. By

this means the rear end is rendered 110

tively narrow so as to retain the oil within the receptacle and at the same time prevent the escape of the oil.

Depending from the bottom of the receptacle are legs 19, said legs being disposed at the front, central and rear portions of the receptacle, so as to hold the receptacle in spaced relation to the bottom face of the journal box and also closely adjacent the journal A. It will be noted that the receptacle is slightly larger than the journal so as to hold a small quantity of oil and yet permit the oil to rise to a level above the center of the journal. By this means only a small portion of the journal projects above the receptacle, the rest of the journal being entirely immersed in lubricant.

To facilitate the application of oil to the receptacle, a plate 20 is hinged to the upper edge of the front wall 14 of the receptacle. Said plate is adapted to extend over the edge of the opening in the front wall to serve as a rest for the spout of a supply oil can when the device is being filled. This cover is also intended to be swung inwardly when the lid 10 of the journal box is closed, so as to cover the oil in the front end of the receptacle, and thereby exclude dust. It also prevents splashing caused by the rotary movement of the journal.

It is of course obvious that the receptacle is substantially semi-circular in cross section, so as to conform to the curvature of the journal A of the axle B. The large semi-circular recess, formed through the co-operation of the recesses 16 and 18, is intended to receive a strip of graphite 21 and a strip of wool or hemp packing 22, the packing being adapted to engage the inner shoulder C of the journal to not only lubricate the same, but to also prevent the lubricant in the receptacle from escaping through the opening 9 of the journal box. Furthermore, the packing is constantly supplied with oil which is directed to the packing from the enlarged portions of the receptacle. The packing 22, however, is relatively small so that there is no possibility of friction being generated to an extent sufficient to cause a hot box.

It will be noted that the front feet of the receptacle are disposed closely adjacent the curved bottom of the journal box so that there is no possibility of the receptacle moving toward the front wall of the journal box. The curved portion of the journal box prevents this. By spacing the receptacle from the bottom and front wall the space between the receptacle and the journal box is free to receive air which assists in preventing overheating. In order to permit the removal of the receptacle when necessary, the front wall 14 of the receptacle is provided with a bail 23, the ends of said

bail being connected to the front wall by means of springs 24 so as to permit the bail to be properly positioned within the journal box without danger of the same coming in contact with the journal A or the lubricant within the receptacle.

From the foregoing it will be readily seen that this invention provides a novel form of lubricating means for journal boxes which does not require a special type of journal box, but which may be placed in any journal box now in use and wherein the journal A is partially immersed in oil without requiring a large quantity of oil for this purpose, in view of the size of the receptacle. Consequently, the receptacle does not require the use of packing for engagement with the major portion of the journal, but only a small strip of packing at each end of the oil cellar to prevent leaking of the oil and at the same time lubricate the inner shoulder of the journal. All of these features are possessed by a device which is compact in form and simple in construction and which may be easily applied.

What is claimed is:—

1. Lubricating means for journal boxes, comprising a lubricant containing receptacle disposed within a journal box, the outer end of said receptacle being closed by a wall and the inner end having an opening accommodating the journal, said inner end being formed to receive packing engaging the journal, and an outwardly and upwardly swingable cover hinged upon the upper edge of the outer end wall of the receptacle and having its free end engaging against the outer end of the journal for excluding dust and preventing splashing of the lubricant.

2. Lubricating means for a journal box, comprising a lubricant receptacle removably mounted within the journal box and having its outer end closed and projecting beyond the journal and having its inner end formed with an opening accommodating the journal, a movably mounted cover at the outer end of the receptacle for closing the space between the outer end of the receptacle and the outer end of the journal, said cover being swingable outwardly to bridge the space between the outer end of the receptacle and the lower edge of the door opening in the box for preventing spilling of oil into the box when filling the receptacle.

3. Lubricating means for a journal box, comprising a lubricant receptacle removably mounted within the journal box and having its outer end closed and projecting beyond the journal and having its inner end formed with an opening accommodating the journal, a movably mounted cover at the outer end of the receptacle for closing the space between the outer end of the receptacle and the outer end of the journal, and a

spring mounted bail on the outer end of the receptacle for facilitating handling, said bail engaging against the outer wall of the box for preventing outward sliding movement of the receptacle. 5

4. Lubricating means for a journal box, comprising a lubricant receptacle removably mounted within the journal box and having its outer end closed and projecting beyond the journal and having its inner end formed with an opening accommodating the journal, a movably mounted cover at the outer end of the receptacle for closing the space between the outer end of the receptacle and the outer end of the journal, the journal box having an opening closed by a movable door, said cover being swingable to lie upon the lower edge of said opening in the
5. Lubricating means for a journal box, comprising a lubricant receptacle removably mounted within the journal box and having its outer end closed and projecting beyond the journal and having its inner end formed to accommodate the journal, a hinged cover at the outer end of the receptacle having its free end normally engaging against the end of the journal and a bail on the receptacle engaging against the inner face of the outer wall of the box, the cover and the bail operating to prevent longitudinal shifting of the receptacle. 10 15 20 25 30

In testimony whereof I hereunto affix my signature.

BERT H. BLOSE.
